CLAIM

The ornamental design for a shoe, as shown and described.

DESCRIPTION

FIG. 1 is a front perspective view of a shoe showing my new design;

FIG. 2 is a side view thereof;

FIG. 3 is a rear perspective view thereof; and,

FIG. 4 is a top view thereof.

The broken line showing of the circular region within the shaded area represents a feature that forms no part of the claimed design. The broken lines depicting the remainder of the shoe show features that form no part of the claimed design.
